TOY CONSTRUCTION ELEMENTS

Walter R. Benjamin, Granite City, Ill., assignor
to W. R. Benjamin Co., Granite City, Ill.

Application February 18, 1939, Serial No. 257,253

3 Claims. (Cl. 46—29)

This invention relates to toy construction elements, and it is an object of the invention to provide elements of this kind including hub members or blocks each having a central opening therethrough and peripherally spaced sockets, said central opening and sockets being of substantially the same diameter, together with two series of rods, the rods of each series being of different lengths with the rods of one series of a diameter and color different from the rods of the second series, the rods of larger diameter engaging within the central opening and the peripheral sockets of each of the hub members or blocks.

15 The invention also has for an object to provide toy construction elements including hub members or blocks having axial openings therethrough with peripheral sockets therearound together with rods of two different diameters to be engaged either tightly or loosely within or through the openings and sockets of the hub members or blocks and wherein are also provided bushings of a size to fit tightly within all of the openings and sockets and into which the rods of smaller diameter tightly engage whereby it is possible 20 with the rods of different diameters and the bushings to make either a tight rigid fit or a loose working fit within the openings and sockets of the hub members or blocks.

25 Another object of the invention is to provide toy construction elements so formed and arranged to afford means whereby various kinds of mechanical motions can be made such as a universal joint, differential, planetary, etc., as well as rigid models of different kinds such as 30 ladders, fences, towers, bridges, etc.

The novel features of my invention will herein-after be definitely claimed.

In order that my invention may be the better understood, I will now proceed to describe the same with reference to the accompanying drawings, wherein—

Figure 1 is a view in perspective illustrating toy construction elements embodying my invention and in an assembly to represent a portable windmill;

Figure 2 is a sectional view taken substantially on the line 2—2 of Figure 1;

Figure 3 is a view partly in top plan and 50 partly in section showing my elements as herein embodied in an assembly to provide a universal joint;

Figure 4 is a sectional view taken substantially on the line 4—4 of Figure 3;

55 Figure 5 is a fragmentary detailed view partly

in section and partly in elevation illustrating the means for splining a hub member or block upon a rod;

Figure 6 is a diagrammatic view illustrating one set of rods;

Figure 7 is a diagrammatic view illustrating a second set of blocks.

As illustrated in the accompanying drawings, my improved construction elements comprise a desired number of hub members or blocks 1 each having axially disposed therethrough an opening 2 and provided in its periphery with a series of circumferentially disposed and equi-distantly spaced sockets 3. These sockets 3 are radially directed with respect to the opening 2 and the 10 diameters of said sockets 3 are the same as the diameter of the opening 2.

The elements, as herein disclosed, also include 15 two series of rods. The rods of each series are of three different lengths and of a desired number. The rods in series A are 4, 5 and 6 and in series B the rods are 7, 8 and 9. The rods 4 and 7; 5 and 8; and 6 and 9 are of the same 20 length and the rods of each series are of the same diameter. The rods 4, 5 and 6 comprised in the series A are of a diameter substantially the same 25 as the diameters of the opening 2 and the sockets 3 of each of the hub members or blocks 1 to tightly engage therein. The rods 7, 8 and 9 of series B are of a diameter less than the diameters 30 of the central opening 2 and the sockets 3 of each of the hub members or blocks in order that said rods 7, 8 and 9 may be freely inserted within or through the opening 2 and the sockets 3.

The rods 4, 5 and 6 of series A are all of the 35 same color or other common identity while the rods 7, 8 and 9 are all of a different color or different identity so that the rods 4, 5 and 6 and the rods 7, 8 and 9 can be readily distinguished by the child using the elements.

The elements also include a desired number of 40 metallic bushings 10 each having a flange 11 surrounding one end thereof. The bore 12 of each of these bushings 10 is substantially the same as the diameter of the rods 7, 8 and 9 in series B whereby a bushing may snugly fit upon 45 any one of such rods. The major diameter of the bushing 10 is substantially the same as the diameter of the opening 2 or the sockets 3 of a member or block 1 so as to have tight engagement therein.

My elements also include the rubber washers 14 to tightly engage around any one of the rods as may be required in an assembly. The elements also include the desired number of blades 50

or fans 15 of heavy paper stock and each of which is preferably square so that the same will give a maximum of surface to the wind and also allowing each edge to be used in placing the blade or fan in position.

5 Each of the rods 4, 5, 6, 7, 8 and 9 has its extremities provided with a kerf 16.

10 The elements also include pulleys 17 each having therethrough a central bore 18 of the same diameter as the bore or opening 2 of each of the members or blocks 1.

15 In Figure 1 of the drawings is illustrated a portable windmill assembled from the various elements as hereinbefore referred to and it is to be noted that the rubber washers 14 are placed upon the various rods 7, 8 and 9 to maintain in proper position thereon for free rotation the applied members or blocks 1. In the windmill assembly, the outer kerfs 16 of the rods 5 comprised in the head structure and the rods 6 comprised in the tail structure have inserted therein the marginal portions of the blades or fans 15, the angle or pitch of said blades or fans being readily determined by the placement of the rods 5 and 6.

20 When it is desired to mount a hub member 1 upon one of the rods 7, 8 or 9, a piece 19 of string or the like may be employed as a key.

I claim:

30 1. Toy construction elements having in combination a hub member having an axial opening therethru and circumferentially spaced sockets in its periphery, said opening and sockets being of the same diameter, two series of rods, the rods of one series being of a diameter substantially the same as the diameters of the opening and sockets of the hub member, the rods of the second series being of a diameter less than the diameters of the central opening and sockets of the hub member, a flanged bushing having a

bore of a diameter to tightly receive a rod of smaller diameter, said bushing being of a major diameter to snugly engage within the opening or sockets of the hub member.

2. Toy construction elements having in combination a hub member having an axial opening therethru and circumferentially spaced sockets in its periphery, said opening and sockets being of the same diameter, two series of rods, the rods of one series being of a diameter substantially 10 the same as the diameters of the opening and sockets of the hub members, the rods of the second series being of a diameter less than the diameters of the central opening and sockets of the hub member, a flanged bushing having a 15 bore of a diameter to tightly receive a rod of smaller diameter, said bushing being of a major diameter to snugly engage within the opening or sockets of the hub member, the rods of each series having common identifying means, the 20 identifying means of one series of rods being different from the identifying means of the second series of rods.

3. Toy construction elements having in combination a hub member having an axial opening 25 therethru and circumferentially spaced sockets in its periphery, said opening and sockets being of the same diameter, two series of rods, the rods of one series being of a diameter substantially 30 the same as the diameters of the opening and sockets of the hub members, the rods of the second series being of a diameter less than the diameters of the central opening and sockets of the hub member, a flanged bushing having a bore of a diameter to tightly receive a rod of 35 smaller diameter, said bushing being of a major diameter to snugly engage within the opening or sockets of the hub member, and rubber washers to snugly fit upon the rods.
